UNITED STATES PATENT OFFICE.

JEAN JOOSTEN AND PIERRE ANDRÉ PERRIN, OF LILLE, FRANCE.

ROTARY ENGINE.

1,262,206.

Specification of Letters Patent.

Patented Apr. 9, 1918.

Application filed January 6, 1914. Serial No. 810,601.

To all whom it may concern:

Be it known that we, JEAN JOOSTEN, a subject of the King of Belgium, and PIERRE ANDRÉ PERRIN, a citizen of the French Republic, residing, respectively, at Lille, Nord, in France, have invented certain new and useful Improvements in Rotary Engines, Pumps, and the like, of which the following is a specification.

10 This invention relates to improvements in rotary engines, pumps, motors, or similar engines.

In the accompanying drawings:

Figure 1 is an elevation of the engine 15 wall the front of the engine casing being removed.

Fig. 2 is a section on the line A—B of Fig. 1.

Fig. 3 is a vertical longitudinal section 20 of the engine.

Fig. 4 is a plan view, the part 1 of the casing shown in Fig. 1 being removed to allow the interior construction to be seen.

Figs. 5 and 6 are sections illustrating the 25 positions of the reversing mechanism of the engine.

1 and 2 are two semi-circular members forming a casing and composing the stator or fixed part of the engine; these two members are connected together by bolts 2^a Fig. 3 and passing through supports 3 and 4 supporting the whole. Four juxtaposed quadrant members 5, 6, 7 and 8 are bolted together by bolts 71 these members having 35 together the appearance of a wheel comprising four arms of which the rim portions 5, 6, 7, 8 are of channel shape and form with the stator chambers the cross sections of which are parts of an annulus as indicated by 72 in Figs. 2 and 3. The parts of the sectors forming the four arms 5^a, 6^a, 7^a, 8^a are hollow and form four chambers for the accommodation of four disks 17, 18, 19, 20 and provided with central axles rotatable in 45 bearings formed on the arms 5^a, 6^a, 7^a and 8^a as can be seen in Fig. 3. These disks project out of their chambers and extend into the rim chambers 72 the peripheries of the disks closely fitting against the channel like wall 50 73 of the stator (Figs. 2 and 4). The stator is provided with five helicoidal partitions 11, 12, 13, 14 and 15 fixed thereto and which divide the space comprised between the stator and rotor into five chambers 72.

55 One end of the axle of each disk extends

through the casing arm which incloses it and these extensions are provided at their ends with beveled pinions 20, 21, 22, 23 which lie in the spaces between the arms and engage with beveled pinions 24, 25, 26, 27 carried by shafts 28, 29, 30, 31, Fig. 4 rotating in bearings 32 (Fig. 2). The other ends of these shafts carry outside the rotor gear wheels 33, 34, 35, 36, which roll on a fixed cog-wheel 37 attached to the bearing 9.

The rotation of the rotor in the bearings thus causes the simultaneous rotation of all the disks 16, 17 18 and 19 on their axles and the angular speeds of the disks and of the rotor are thus in constant relation. The dimensions of the gear wheel are such that in the machine illustrated each disk makes exactly five complete revolutions on its axis while the rotor which carries them makes one revolution. The relation of the angular speeds being a whole number it results that the disks follow the same path at each revolution of the rotor. In particular the path described by any radius of a disk is a closed helicoidal surface.

Each disk is provided with a single radial notch 38, 39, 40, 41 of helicoidal shape determined by the relation of the angular speeds of the disks and rotor, and each fixed partition 11, 12, 13, 14, 15 is of a helicoidal shape corresponding to the path traced in the chamber by the passage of the helicoidal notches of disks and is fixed at the very place of the passage of these notches into the chambers 72. Consequently, during rotation of the rotor the fixed partitions, although they completely close the chamber 72, are not an obstacle to the passage of the disks, the helicoidal notches of the disks arriving at the required moments so as to slide over the fixed helicoidal partitions in the same manner as a nut-thread slides on a screw-thread.

The depth of the notch of the disks is limited to the depth of the chambers 72, so that the helicoidal fixed partitions completely close the helicoidal notches of the disks when the disks are passing by.

The chambers 72 perform the functions of the cylinder *y* of a reciprocating engine and the disks the functions of pistons. In the engine illustrated which is an explosion motor 42, 43, 44, 45, 46, 47 (Figs. 3 and 4) are the orifices for passage of the gases. 69 and 70 are holes pierced in the disks 16

and 18 opposite to the notch and which at the moment of their passage between the conduits 53, 54, 52, and 55 allow the passage of the gases from one side to the other of the disk. 48, 49, 50, 51 (Fig. 1) are the inlet and the outlet conduits for the gases and 52, 53, 54, 55 are the pipes for the passage of the gases from one side to the other of the same disk.

10 60, 61, 62 and 63 are the sparking plugs. 64 (Figs. 2, 5 and 6) is the central admission pipe for the gases which has its orifice between two pistons 65, 66 obstructing the central passage 64^a of the shaft. The conduits 48 and 49 are divided into two branches before reaching the central passage 64^a and the conduits 50 and 51 are connected with the central passage between the two branches of the conduits 48 and 49. According as it is desired to effect the admission through the conduits 48 and 49 or 50 and 51 that is to say for reversing the rotation of the motor the pistons 65 and 66 are so displaced that they comprise between them the orifices of the one or the other conduits. The gases are exhausted through the orifices left exposed behind the piston 65 and leading to the annular space left free between the central admission pipe 64 and the central passage 64^a of the shaft. In the case of admission through pipes with double orifices an annular plug 67 mounted on the central admission pipe stops the supplementary orifices which otherwise serve for exhaust. The unused side of the shaft-passage is closed by a plug 68.

15 Oiling is effected under pressure by the ordinary means and gas tightness between the various members of the machine is effected by packing in the usual manner.

20 The improved engine can have any suitable number of disks but it is to be noted that in order to avoid the disks passing the helicoidal partitions at the same time, which 25 would cause as many dead points per revolution as there are disks, it is necessary that the number of the helicoidal partitions should be always one more than the number of disks.

25 30 The engine works as follows:—

Assuming that the rotor is rotating in the direction of the arrow (Fig. 3) then the spaces comprised between the partition 13 and the disk 17 and the partition 15 and the disk 19 are increased and in these spaces the gases are being sucked in entering therein through the orifices 42 and 43, fed through the conduits 48 and 49, which are connected to the central passage 64^a between the two pistons 65 and 66 of the admission pipe 64. The machine continuing its rotation fresh gases fed through the orifice 42 begin to fill the space comprised between the helicoids 12 and 13, then the disk 17 passes the helicoid 12 while continuing to

suck the gases behind it, there being a continuous suction through the orifice 42; the disk 17 sucks the gases into all the chambers 72 consecutively—the disk 19 acts in the same way on the orifice 43.

70 The disks 18 and 16 drive before them the sucked-in gases—these gases endeavor to pass into the conduits 54 and 55 (Fig. 1) through orifices arranged like 45 (Fig. 4), but the conduits 54 and 55 are obstructed by the disks, the gases are therefore compressed until the moment when the disks begin to pass the helicoids. The dimensions of the chambers are so calculated that the compression at this moment reaches the suitable 80 value. From this moment and during the whole time of passage past the helicoidal partitions the disks 18 and 16 bring the bores 70 and 69 between the conduits 54, 53, and 52, 55 and the gases then commence 85 to pass from the space comprised between the front face of the disk and the rear face of the helicoidal partition into the space comprised between the rear face of the disk and the front face of the helicoidal partition 90 when the helicoidal partition is passed the gases will be behind the disks at the same compression, since the space is exactly symmetrical with the former with respect to the disk. At this moment the spark is 95 produced at the plugs 62 and 63 and the disks are driven forward, the conduits 53 and 52 being then closed. The gases expand and the disks 18 and 16 will leave them burnt behind them. At each helicoidal 100 partition the operation will recommence.

Reverting now to the disks 17 and 19, their front faces begin to drive before them the burnt gases, the conduits 50 and 51 being constantly open by means of the orifices 44 105 (Fig. 4), and the burnt gases pass into the annular passage 64^a and thence to the open air.

To sum up, the disks 17 and 19 continually expel before them the burnt gases and 110 continually fill the spaces behind them with fresh gases, the disks 18 and 16 compress the gases in front of them and these gases are exploded behind them. The suction and exhaust of the gases are continued through 115 the same orifices.

If the engine is reversed the same operations are repeated in the reverse manner.

The engine is economical as regards the use of fuel and gives great power for a small size and weight. It is particularly suitable for automobiles as owing to its flexibility it permits of easy and progressive starting. By reversing it and causing it to act as compressor, it may be employed to brake either 125 the wheels or the Cardan shaft of an automobile in a powerful, progressive and rapid manner.

It is also suitable for aviation and navigation purposes.

What we claim as our invention and desire to secure by Letters Patent of the United States is:—

1. In a device of the character described, 5 the combination of a rotor, a stator surrounding said rotor and adapted to form together therewith an annular chamber of circular cross section, helicoidal partitions fixed to said stator dividing said chamber 10 into a series of working chambers, a series of rotatable disks provided with lubricating passages carried by said rotor of a number different from the number of working chambers and projecting into said chambers 15 on planes at right angles to the longitudinal planes of said working chambers, means provided in certain of said disks for the supply of explosive mixture to and the exhaust of burnt gases from said chambers to impart 20 part rotary motion to said disks about the axis of the rotor, means provided in certain other of said disks to allow compressed gas from one working chamber to its neighbor, and bevel wheel gearing for imparting rotary motion to said disks about their respective axes, each of said disks being provided with a peripheral notch allowing said disks to pass said helicoidal partitions during their movement.
  2. In a device of the character described, 30 the combination of a hollow shaft, a boss mounted thereon, a series of equally distanced radially arranged arms mounted on said boss, a circular channel shaped flange 35 carried by said arms, an annular chamber
- surrounding said flange, a series of helicoidal partitions fixed within said stator dividing said annular chamber into a series of equal working chambers, bearings carried by said axles, a series of rotatable disks 40 each provided with a peripheral notch and partially inclosed in said arms and projecting into said annular chamber on planes disposed at right angles to the plane of said annular chamber and forming movable partitions in said chamber, axles carrying said disks, means for admission and means for exhaust of motive fluid for one half the number of said working chambers to impart 45 rotary movement to said disks about said shaft, means enabling the gases compressed between a said movable partition and a said fixed helicoidal partition to pass behind said movable partition, means for imparting rotary movement to said disks about said axles, 50 means for conveying lubricant to said axles and said disks, means for preventing leakage of fluid from said working chambers, and means comprised in said hollow shaft for reversing the direction of rotation of 55 said disks about said shaft.
- In witness whereof we have signed this specification in the presence of two witnesses.
